The ornamental design for vehicle front wheel face, as shown and described.

DESCRIPTION

FIG. 1 is a perspective view of a vehicle front wheel face according to my new design;

FIG. 2 is a front elevational view thereof; and,

FIG. 3 is a side elevational view thereof.

The broken lines showing the side of the wheel and the bolts and center cap in the central hub area are included for the purpose of illustrating environment and form no part of the claimed design.
